3 Claims. (Cl. 66—96)

1

The present invention relates to straight knitting machines provided with automatically operating picot bar and patterning point devices for producing the picot edge and a mark during the knitting of the welt of a stocking.

In a prior single needle-bank straight knitting machine having a standard narrowing device which operates periodically in the calf portion, the heel and the toe portion of a stocking, and a picot bar and patterning point device, which is operative during the knitting of the welt of a stocking, it has been proposed to cause the picot bar, after a pattern row or the picot edge has been prepared, to swing automatically upwards under the action of a coiled spring so as to move it to its inactive position.

The exact adjustment of such a coiled spring requires some attention in order to secure a uniform decrease of the speed of the picot bar in its returning movement from its active to its inactive position and to avoid a violent impact of the picot bar against the protecting device. One or more such impacts may produce after a time such an unfavourable change in the working position of the picot bar that after a certain period of operation the needles of the picot bar do not occupy any more their exact position over the corresponding knitting needles. For the reasons referred to, it may also happen that the picot bar when swinging in upward direction will not reach its inactive position, so that the picot or lace needles will come to rest outside of the protecting device and may injure the operator when the latter hangs over the welt by hand. The just described arrangement also requires that the picot bar be swung down by hand to its active position in which it is locked by a dog clutch.

Furthermore, it has been proposed to provide in connection with a multi-needle-bank straight knitting machine an automatically operating picot bar device in which the picot bars, under the action of a tension spring, are rocked automatically downwards to their active position prior to the formation of the picot edge. But neither this arrangement provides for a uniform movement of the picot bars, and the suddenly freed energy of the tension spring produces rather an acceleration of the downwardly rocking picot bars so that undesirable impacts and displacements take place. Moreover this arrangement requires that a special driving device should be interposed between the pawl and ratchet mechanism and the transmission gearing; the said driving device comprises a pattern chain which is provided with sectors and by means of a lever system is adapted

2

to move the picot bars to their active and inactive position.

As compared with these known constructions the new feature of the invention, which brings an appreciable technical advance in the art, consists in that the automatic movement of the picot bars or of the pattern narrowers to their active and inactive position is effected positively by means of a pawl and ratchet device and a transmission gearing. In this arrangement the transmission gearing is driven directly by the pawl and ratchet device. Preferably one or more members of the transmission gearing, e. g. toothed wheels, are provided in one of their end faces with a groove of spiral shape in which studs fastened on rack bars are guided in such a way as to obtain a uniform, self retarding, reversible movement of the picot bars or of the patterning points. The main advantage of the use of a spiral shaped groove consists in this that both lateral walls of the groove act in both directions upon the stud of the rack bar, this provision leading to a substantial simplification of the entire driving mechanism.

By a suitable choice of the pitch of the spiral shaped groove, it is possible to obtain any desired transmission ratio. The apparatus is capable of exact adjustment and self retardation also in the end positions. The sequence, the start and the duration of the operation of an automatically working picot bar and patterning point devices is controlled by a member common to both devices, e. g. a rotatable wing, the appropriate adjustment of which is effected by means of a lever system from a cam on the main cam shaft, or by means of a cable section from the usual pattern drum or pattern chain.

The details of the subject matter of the invention are set out in the following description of the embodiment which is shown in the accompanying drawings, where

Fig. 1 is a diagrammatic illustration of the apparatus, the partially shown picot bar being in its active position and the patterning point device in its inactive position;

Fig. 2 is an elevation showing the arrangement of a picot bar, of a patterning point device and of the normal narrowers, with their common driving means in the range of a working station (needle row);

Fig. 3 is a section along the line I—I of Fig. 2;

Fig. 4 is a plan view corresponding to Fig. 2, and

Fig. 5 is a view showing the picot bar in the

lower active position in full lines and in the upper inactive position in dotted lines.

The picot bar or comb 1 of known construction shown in Fig. 1 carries the points 2 and by means of brackets 3 is mounted on a rock shaft 4. As usual, each point 2 of the picot bar or comb 1 is positioned over each alternate knitting needle, when the picot bar is in its active position.

The shaft 4, carrying the picot bar by means of the brackets 3 which are pinned on the said shaft, is rotatably mounted in the arms 5 of the narrowing device which moves up and down at suitable intervals. A portion of the shaft 4 is provided with gear teeth 6 co-operating with the teeth of a rack bar 7 which is guided vertically in a suitable bearing (not shown). A stud 8 carried by the rack bar 7 engages in a groove 9 which is provided, e. g. in the shape of an Archimedean spiral, in one of the end faces of a toothed wheel 10. The spiral shaped groove becomes broader at its end close to the center point of the rotating axis. The toothed wheel 10, which is mounted rotatably in cantilever fashion in a bearing 11, meshes with the teeth of a pinion 12 which is mounted for free rotation on a shaft 13 of the narrowing device. The shouldered hub of the pinion 12 carries two ratchet wheels 14, 15 which are adapted for engagement with the respective pawls in opposite senses with respect to each other. A portion of the periphery of each ratchet wheel is not provided with teeth. A wing 16, which is mounted for free rotation on the hub of the pinion 12 between the two ratchet wheels 14 and 15, controls the engagement of either pawl 17 or 18 with the teeth of the respective ratchet wheel and so determines the sense of rotation of the ratchet wheels. The pawl 17 and the cooperating ratchet wheel 14 serve for rotating the pinion 12 in the clockwise direction while the pawl 18 and the corresponding ratchet wheel 15 serve for rotating the pinion 12 in the opposite direction. The movement of the wing may be derived from a control drum or a pattern chain (which are not shown), or from a control device allotted to the said wing (also not shown). The pawls 17 and 18 are freely rotatable about a pivot pin 19 carried by a lever 20 which is mounted for rocking movement on the shaft 13 of the narrowing device.

On a pin 21 fastened to the lever 20 there is mounted for free rotation a draw bar 22 whose movement is derived from a cam on the main cam shaft by means of a lever system which is not shown in the drawings. The working position of the picot bar 1 is determined by a single arm lever 23 which is pinned on the shaft 4 in such a way that the tooth 24 of the lever 23 bears against the end of a spring supported safety member 25 which is mounted rotatably about a pin 26 fastened in the arm 5. A spring 27 fastened to the underside of the safety member 25 bears with its free end against the bottom of a recess provided in the arm 5 and urges the free end of the safety member 25 towards the tooth 24. The safety member 25 is provided with a notch 28 adapted to receive one end of a pin 29, the other end of the pin being fastened in the bar of the narrower 30. A stud 31 guided in the bracket 3 and bearing against beam member 32 is surrounded by a compression spring 33 the free end of which bears against the bottom of a bore provided in the hub portion 34 of the bracket 3.

A patterning point device 35, known per se

and provided with one or more needles 36 for the production of marks, is mounted rigidly on a rocking shaft 37 which may be driven in part by the means used for the drive of the rock shaft 4.

The combined drive of the two devices for producing the picot edge and following thereto the marks, or vice versa, during the knitting of the welt, which drive is derived from a central position, e. g. from a pattern drum, a pattern chain or from a control device associated with the above mentioned two devices, requires in addition to the said two ratchet wheels 14 and 15 two further ratchet wheels 38 and 39 with corresponding pawls, and an enlargement of the upper part 40 of the wing 16, as it is shown in Figs. 2 to 4. The ratchet wheels 38 and 39 are keyed on the hub of the pinion 41 which is mounted for free rotation on the shaft 13. The pinion 41 meshes with a gear 42 fastened on a counter-shaft 43, the other end of the counter-shaft having keyed thereon a gear 44 which meshes with a gear 45 mounted for free rotation on the shaft 13. The gear 45 co-operates with a gear 46 which is mounted in cantilever fashion in a bearing 47. A groove is formed in the end face of the gear 46 to receive a pin 48 carried by a rack bar 49 which is guided vertically in a bearing, not shown in the drawing, and engages with teeth 50 provided on the shaft 37 whereby the patterning point device 35 with the needles 36 is moved automatically at the proper moment to its active or inactive position.

The automatic downward movement of the picot bar, which takes place in the middle of the length of the welt, into active position is effected as follows:

A cam (not shown) of the main cam shaft actuates a lever system connected to the link 40 22 (Fig. 1) which thus receives a reciprocating movement and causes the lever 20 and the pawls 17 and 18 to rock about the shaft 13. On the wing 16 being automatically turned and adjusted from a control drum or a pattern chain, not shown in the drawing, the said wing 16 uncovers by a portion of its upper part the teeth of the ratchet wheel 14 and at the same time covers with the other portion of its upper part the teeth of the adjacent ratchet wheel 15. In this manner engagement of the pawl 17 with the ratchet wheel 14 is permitted while the adjacent pawl 18 slides in inactive position along the upper part of the wing 16. As a consequence, the pinion 12 will be rotated in clockwise direction, as viewed in Fig. 1, and the gear 10 will be rotated in the opposite direction. Owing to the simultaneous rotation of the spiral shaped groove 9, the stud 8 and rack bar 7 are urged towards a larger radius, i. e. in downward direction, so that the teeth 6 of the shaft 4 will revolve in the clockwise direction and the bar 1 will be lowered thereby to its working position. Before the rotation of the shaft 4 in the clockwise direction is terminated, the safety member 25 will engage behind the tooth 24 of the rotating lever 23 and thus will lock the latter and with the same also the bar 1 in the working position. In Fig. 1 the apparatus is shown in position upon termination of the movement just described.

Since after expiration of a certain period some play may appear in the gearing, it would be difficult to obtain an exact adjustment of the points 2 of the bar 1 over the knitting needles. In view 75 of this circumstance, the above described ap-

paratus is operated in such a way that the bar, during its downward movement, passes beyond its working position in a direction towards the interior of the machine. However, as soon as the end of the spring controlled safety member 25 has engaged behind the tooth 24 of the lever 23, the play between the stud 8 and the inner walls of the broadened spiral shaped groove 9 will enter in action upon a further rotation of the said groove and the spring 33 will force the bar 1 back to its working position.

For the oscillatory movement of the toothed wheel 10 provided with the spiral shaped groove 9, in order to return automatically the bar 1 to its inactive position, it is necessary that the angle of rotation of the toothed wheel 10 should be always the same, as otherwise the described apparatus may be damaged. To achieve this result the ratchet wheels 14 and 15 are not provided with teeth over their whole circumference so that as soon as the spiral shaped groove 9 has rotated through the required angle, e. g. to bring the bar to its working position, the corresponding ratchet wheel 14 is not rotated any more because the pawl cannot engage with any tooth. Owing to this arrangement it is not necessary to interrupt the feeding movement of the link 22 and the whole operation of the apparatus as above described is controlled merely by the automatic adjustment of the wing 16 for momentary engagement of one or the other of the pawls with the corresponding ratchet wheel.

The automatic raising of the picot bar into inactive position, when the meshes have been transferred to the knitting needles, is effected as follows:

By the movement of the narrower 30 towards the middle of the needle row the pin 29, which is carried along by the narrower, is liberated due to its lateral movement from the notch 28 and presses against the free end of the safety member 25 in a downward direction so that the tooth 24 of the lever 23 becomes disengaged from the said member. The simultaneous automatic rotation of the wing 16 causes the teeth of the ratchet wheel 14 to be covered by one portion of the upper part of the wing while the other portion of the upper part of said wing will uncover the teeth of the adjacent ratchet wheel 15. The pawl 17 begins to slide in inactive position on the upper part of the wing 16 while the adjacent pawl 18 will engage with an anticlockwise movement with the teeth of the ratchet wheel 15. The pinion 12 will rotate counter-clockwise and the gear wheel 10 will rotate in the opposite direction. Due to the simultaneous rotation of the spiral shaped groove 9 in clockwise direction, the stud 8 and the rock bar 7 are raised so that the teeth 6 of the shaft 4 will rotate in counter-clockwise direction and thereby the bar 1 will be raised to its inactive position.

The working method of the common drive, controlled from a single (central) station, for the automatic lowering and raising of the patterning point device with the marking needles 36, which operation takes place when the picot edge has been made, is similar to the just described method for the automatic lowering and raising of the picot bar 1. The method may be followed in Figures 2 to 4, and consists in this that in the

inactive position of the bar 1 the wing 16 occupies such a position that one portion only of its broad upper part 40 (Fig. 2) uncovers the teeth of the ratchet wheel 38 or 39. The respective pawl (not shown) will engage with one of the said ratchet wheels and cause the pinion 41 to rotate in counter-clockwise direction as viewed in Fig. 3. The cooperating gear wheel 42 with the counter-shaft 43 and the gear wheel 44 rotate in clockwise direction. The rotary motion of the counter-shaft is transmitted over the gear wheel 45 to the gear 46 (Fig. 4) which is rotating anti-clockwise. By the simultaneous rotation of the spiral shaped groove in the toothed wheel 46, the stud 48 and rack bar 49 are urged downwards so that the teeth 50 on the shaft 37 revolve in clockwise direction and as a consequence the bar 35 with the marking needles 36 is lowered to its active position.

The automatic raising of the bar 35 with the marking needles 36 to inactive position is similar to the lowering operation just described. For this purpose automatic adjustment of the wing 16 is required to such a position as to cause reversal of the sense of rotation of the pinion 41 and thus of all the co-operating members of the transmission gearing.

The apparatus in accordance with the present invention is not limited to the example shown and described and may be modified in various directions within the scope of the appended claims.

What I claim is:

1. In a straight knitting machine, automatically operating picot and patterning point devices for the production of a picot edge and of a mark during the operation of knitting the welt of a stocking, a pawl and ratchet mechanism comprising a link, a lever, driving pawls and ratchet wheels and associated transmission gearing adapted to be driven directly by the ratchet wheels and comprising toothed wheels provided with spiral shaped grooves and rack bars with studs carried by the latter and guided in the said grooves in such a way as to cause the rack bars to move in a self retarding manner to and fro along their longitudinal axes so as to automatically and positively move the picot bar and the patterning points, respectively, of the said devices into active and inactive positions, and a rotatable wing for controlling the said pawl and ratchet mechanism.

2. The straight knitting machine as set forth in claim 1, in which the said ratchet wheels are adapted to be rotated in opposite directions.

3. The straight knitting machine as set forth in claim 1, in which the spiral shaped grooves are formed as Archimedean spirals.
